UNITED STATES PATENT OFFICE.

CHARLES MOORE, OF NEW YORK, N. Y., ASSIGNOR TO HENRY C. SERGEANT
AND GEORGE R. CULLINGWORTH, OF SAME PLACE.

PRESSURE-REGULATOR FOR AIR, &c.

SPECIFICATION forming part of Letters Patent No. 234,051, dated November 2, 1880.
Application filed March 30, 1880. (No model.)

To all whom it may concern:

Be it known that I, CHARLES MOORE, of the city of New York, in the county and State of New York, have invented a certain new and useful Improvement in Pressure-Regulators for Air, Gas, &c., of which the following is a specification.

My invention consists in the combination, in a pressure-regulator for air or gas, of a chamber, a bridge-piece extending across said chamber, a receiving passage or duct and a delivery passage or duct in said bridge-piece, a valve adapted to close against the mouth of the said receiving passage or duct, a diaphragm in said chamber, rods connecting said valve and diaphragm and extending upon opposite sides of said bridge-piece, and a spring and adjusting-nut for setting the regulator to the desired pressure.

20 In the accompanying drawings, Figure 1 represents a central vertical section of a regulator embodying my improvements, and Fig. 2 represents a corresponding section on the dotted line *x x*, Fig. 1.

25 Similar letters of reference designate corresponding parts in both the figures.

A designates the chamber of the regulator, provided with a receiving duct or passage, *a*, for the entrance of air or gas, and a delivery duct or passage, *b*, for the outflow of air or gas. As here represented, both of said ducts or passages pass outside the chamber through screw-threaded hubs *B* to facilitate the connection of air or gas pipes, and the inner portions of both are formed or contained in a bridge-piece, *C*, which extends across the chamber, but which is of small diameter, so as to allow a plentiful circulation of air or gas around it.

40 D designates a valve arranged in the chamber *A* and adapted to seat against the inner mouth of the receiving duct or passage *a*.

E designates a diaphragm, of flexible material, extending across the chamber *A* and adapted to be acted upon by the air or gas contained in said chamber to close said valve. 45

F designates a spring arranged to act upon the side of the diaphragm opposite to that acted on by the air or gas, and having a tendency to open the valve *D* to permit the passage of air or gas through the regulator.

The diaphragm *E* is connected to the valve *D* by means of a yoke formed by rods *e*, arranged one on each side of the bridge-piece *C*. In order to provide for properly regulating the degree of pressure which the regulator is intended to maintain, I provide for increasing or diminishing the resilience of the spring *F*, and, as here represented, this is done by means of a screw-plug, *G*, which is made hollow to receive the spring *F*, and screws into the cap or bonnet *H* of the regulator. 60

I designates a stem or rod extending upward from the diaphragm *E* through the plug *G*, and serving to properly center and guide the valve *D* and other parts in their movements. 65

As the valve *D* moves with the pressure instead of against it in opening, the regulator is much more sensitive to slight variations in pressure.

70 What I claim as my invention, and desire to secure by Letters Patent, is—

The combination of the chamber *A*, the bridge-piece *C*, the receiving-duct *a* and delivery-duct *b* in said bridge-piece, the valve *D*, 75 adapted to close against the mouth of the duct *a*, the diaphragm *E*, the rods *e*, connecting said valve and diaphragm, the spring *F*, and screw-nut *G*, all substantially as specified.

CHARLES MOORE.
